MOSES G. CRANE, OF NEWTON, MASSACHUSETTS.

Letters Patent No. 80,922, dated August 11, 1868.

IMPROVEMENT IN ELECTRO-MAGNETIC ALARMS.

The Schedule referred to in these Letters Patent and making part of the same.

TO ALL WHOM IT MAY CONCERN:

TO ALL WHOM IT MAY CONCERN: Be it known that I, MOSES G. CRANE, of Newton, in the county of Middlesex, and State of Massachusetts, have invented an Improved Magnetic Bell-Striking Apparatus; and I do hereby declare that the following, taken in connection with the drawings which accompany and form part of this specification, is a description of my invention sufficient to enable those skilled in the art to practise it.

The invention relates to the construction and arrangement of the striking-mechanism of electro-magnetic alarm-bells, and consists primarily in combining with the magnet, and the locking and releasing mechanism, through which, by the vibration of the armature, the bell-hammer is alternately released to be thrown against the bell, and locked after giving its blow, a counterbalanced hammer so arranged that it is thrown with a slight force to effect a quick and impulsive blow.

The drawings represent a magnetic bell-striking apparatus embodying my improvements.

A shows a front elevation of the mechanism.

A shows a front elevation of
B is a side elevation thereof.

B is a side elevation thereof.
 a denotes the bell; b , the magnetic coil; c , the armature, the shaft d of which is pivoted in bearings in a frame, e , in which frame is also mounted the winding-arbor f , of a barrel, g , upon which is wound the cord h , to which the weight i is suspended. On this arbor f is fixed a gear, k , which meshes into and drives a pinion, l , on a shaft, m , which shaft has a crank-arm, n , jointed to a link, o , the opposite end of which is jointed to an arm, p , of the hammer-lever q , as shown in the drawings. The lever q swings loosely (when not locked) on a pin, r , and an arm, s , extends from the lever above the fulcrum r , this arm having a weight, t , secured to or forming part of it, this weight counterbalancing the weight of the hammer u . When the crank n is released, the stress of the weight turns the gear and through it the pinion, first throwing the hammer back, and then impelling it forward, (as the link is thrown down,) and as the weight of the hammer is thus counterbalanced, only a very slight force is necessary to throw the hammer forward against the bell. The pinion l may therefore be made very small relatively to the gear-wheel, thereby greatly increasing the number of blows effected by a certain range of movement of the actuating-weight.

The armature-bar extends back from its fulcrum d , as seen at v , the armature being held normally from the magnet b , by the spring w . The arm v has a tripping-mechanism for effecting the blows of the hammer through the armature, as follows:

Two pins, x , y , extend out from the arm v as seen at A and B, these pins being arranged, one higher than the other, and one nearer to the end of the lever than the other.

From an extension, z , from the crank-arm n , a finger, x , projects, and in the normal position of the armature; the pin x is in the path of rotation of this finger, while, when the armature is drawn to the magnet, the pin y is in this path of rotation, so that each pin stops the rotation of the crank, the arm v vibrating between stops b and b' . The arm v is against the pin x . When the circuit is closed, the armature is attached to

Normally the finger a^2 rests against the pin x . When the circuit is closed, the armature is attracted to the magnet, throwing down the opposite end of the arm v , and allowing the finger to escape and swing past the pin x , the finger then bringing up (the arm being still down) against the pin y . When the circuit is again broken, the magnet ceases to attract the armature, and the spring draws the arm v up against the upper stop b^2 , carrying the pin y above the finger a^2 , the escaping finger and the crank then flying round by the stress of the weight which effects the blow of the hammer, the finger bringing up again against the outer pin x . A spring, e^2 , may be placed on the arm v , the finger slipping by the end of the spring, which then flies out and prevents back movement of the finger and crank. Thus, a single rotation of the crank is effected at each breaking and closing of the circuit, and the hammer is securely locked from movement excepting at each complete reciprocation of the armature, the engaging and disengaging-mechanism being perfectly simple and effective.

In some fire-alarm-telegraph systems, the circuit is kept closed, and in such a system it will be seen that as the armature is normally held against the magnet, the finger a^2 is normally against the stop or pin y . Now, if the circuit is accidentally broken, from any cause, the armature will drop from the magnet, releasing the

finger, and allowing the crank to fly around, striking the bell once, and giving notice of the break, the finger bringing up against the outer pin x , and remaining there until the circuit is again closed, when it slips by the stop x , and brings up again against the pin y .

I claim, in combination with the electro-magnet and its armature, the balanced hammer, connected with the armature-mechanism, and arranged to be operated substantially as shown and described.

I also claim, in combination with the striking-mechanism, the stops x y , and finger α^2 , or an equivalent locking and disengaging-mechanism, substantially as described.
